UNITED STATES PATENT OFFICE.

JOHN HOWARD WAY, OF ST. DAVIDS, PENNSYLVANIA.

DESIGN FOR A FLAT-KNIT NECKSCARF.

41,519.

Specification for Design.

Patented June 27, 1911.

Application filed February 26, 1909. Serial No. 480,293. Term of patent 7 years.

To all whom it may concern:

Be it known that I, JOHN HOWARD WAY, a citizen of the United States, residing at St. Davids, in the county of Delaware and State of Pennsylvania, have invented a new, original, and ornamental Design for Flat-Knit Neckscarfs, of which the following is a specification, reference being had to the accompanying drawing, forming part thereof.

The figure is a plan view of a flat knit neck-scarf showing my new design.

I claim:

The ornamental design for a flat knit neck-scarf, as shown.

JOHN HOWARD WAY.
